UNITED STATES PATENT OFFICE.

JAMES F. PATTON AND JOHN E. McALLISTER, OF CLEVELAND, OHIO; SAID McALLISTER
ASSIGNOR TO SAID PATTON.

MILLING MACHINE FOR CONTINUOUS MILLING.

Application filed April 30, 1920. Serial No. 377,933.

To all whom it may concern:

Be it known that we, JAMES F. PATTON and JOHN E. McALLISTER, both citizens of the United States, residing at Cleveland, in the State of Ohio, have invented certain new and useful Improvements in Milling Machines for Continuous Milling, of which the following is a specification.

Our invention relates particularly to a machine which operates upon formed blanks to convert them into castellated nuts. In general castellated nuts are hexagonal in form at their base and are provided with an upper cylindrical portion. Through a portion are milled slots which are perpendicular to the lines forming the sides of the formed blanks. It is an object of our invention to mill these slots in the formed blanks.

Various objects and advantages of our invention will be set forth hereinafter.

In general the invention consists of a machine into which blanks are introduced and by which they are fed past a cutter which cuts a slot therein. After being cut the blanks are rearranged and so forced to another slotting device which produces a slot at an angle to the first slot. After the second slot the blanks are rearranged and so forced to another slotting device which produces a slot at a predetermined angle to the previous slots.

In one aspect the present invention contemplates feeding the nuts forward during this operation in a direct line and producing slots at predetermined angles in the blanks without actually moving the blanks themselves at a corresponding angle.

For the purpose of more fully disclosing the nature and advantages of our invention, we will describe the specific embodiments thereof illustrated in the accompanying drawings. It should be understood, however, that the invention is capable of various modifications and, therefore, it is not limited to the particular structures illustrated.

In the accompanying drawings Figure 1 is a front elevation of one form of the machine, parts being broken away to show details. Fig. 2 is a plan view of the machine shown in Fig. 1, parts being omitted or broken away to show details. Fig. 3 is a transverse longitudinal section of Fig. 2 showing the arrangement of operating gears.

Fig. 4 is a fragmentary vertical section of a mechanism for rearranging the blanks. Fig. 5 is a face view of an adjustable worm. Fig. 6 is an end view of the channel. Fig. 7 is a detached plan view of a part of the rearranging mechanism associated with the mechanism for forcing the blanks toward the cutter. Fig. 8 is a front elevation of another embodiment of the invention. Fig. 9 is a plan view of the embodiment shown in Fig. 8. Fig. 10 is an end view of the channel of Figs. 8 and 9.

A hopper or chute 1 is shown in which the formed blanks 2 may be placed with the sides of their bases in contact. From the chute the formed blanks may drop into pockets in a feed wheel 3 which is mounted on a shaft 4 and rotated as hereinafter described.

As more clearly shown in Fig. 7 the feed wheel consists of a central cylinder 7 between two flanges 8. The flanges are provided with inwardly extending teeth 9. It will be seen that the teeth 9 are beveled at their inner ends so as to correspond to the forms of the formed blanks 2. It will be understood that the teeth 9 illustrated in Fig. 5 are adapted for the particular formed blanks 2 shown in the drawings. Formed blanks of other sizes or other contours may be accommodated by substituting for the teeth 9 herein shown other suitably formed teeth, or other suitably formed feed wheels 3 may be employed.

A channel 10 is at right angles with the axis of the feed wheel 3 so that as the wheel rotates it forces the formed blanks 2 through the channel. The channel may be of any suitable length and at a proper point in it is a cutter 11 which is adapted to be rotated in a manner hereinafter described and to cut a slot across one diameter of the formed blanks as they pass by the cutter. In the particular embodiment of the invention shown in the drawings the cutter consists of the usual disc mounted over the channel 10 and acting upon the tops of the formed blanks as they are passed under the cutter.

The channel 10 may be provided with retaining plates 12 which hold the formed blanks in the channel. These retaining plates do not at all times bear upon the formed blanks but allow them free passage and at

the same time prevent the formed blanks from buckling or turning or being forced up. The retaining plates do, however, allow the nuts or formed blanks some freedom.

5 These plates are shown toward the right of Fig. 2 but are broken away at the left to more clearly show what is underneath.

As shown in Fig. 6 the retaining plates 12 are supported by removable side pieces 10 52 for the channel 10 set in the bed casting. Screws 53 hold the plates and side pieces in place. In the channel 10 the nuts as they move along rest on a bottom plate 54 which may be specially hardened to stand the wear.

15 It will be observed that the teeth 9 of feed wheel 3 are formed and arranged to grasp the formed blanks in such a way as to force them forward while in direct contact with each other on their sides in contradis-

20 tinction to their angles. The relative proportions of the teeth, feed wheel and formed blanks is such that after the formed blanks leave the hopper they are always in contact with each other so that there is a con-

25 tinuous train of formed blanks passing through the channel and they are forced under the cutter by a continuous forward movement and not by an intermittent movement. The arrangement of the formed blanks in the 30 channel and when the cutters act upon the formed blanks is such that the slot milled in the formed blanks is perpendicular to two of the side faces of the formed blanks.

In order to complete the milling operation 35 of the formed blank, which require the milling of two additional slots at an angle with reference to the first milled slot, it is necessary to feed the formed blanks, when once cut, at an angle to their first cut and then 40 again at an angle to the first and second slots. It is obvious that if several cutting mechanisms are arranged to act upon the formed blanks in their movement when so turned each blank will have in it three milled

45 slots extending directly across the formed blanks and perpendicular to the side faces of the formed blank. The blanks when turned might be passed through channels parallel with or at an angle to the channel 50 10 but it is preferred to pass them through a continuation of the channel 10. Associated with the continuation of the channel 10 are corresponding cutters 11. It may be found desirable to associate with each of the additional cutters 11 a separate feed wheel 3 but this is not essential.

In order to ensure that the formed blanks will be turned properly after each cutting a transfer wheel 13 is shown adjacent the path 60 of the formed blanks and arranged to receive the upper edge of the hexagonal portion of a formed blank between each pair of points. The transfer wheel 13 is fastened to a holding down plate 14 which is mounted 65 on a vertical shaft 15 carried in a housing 16

within which is a spring 17 surrounding the shaft and pressing downward upon an enlargement 18 thereon. At the top of the housing is a slot 19 in which may rest a transverse pin 20 to hold the shaft 15 from turning. By means of the handle 21 the shaft 15 may be lifted against the pressure of the spring 17 so as to bring the transfer wheel above and out of contact with the formed blanks or their hexagonal lower portions. The channel 10 is shown curved at 22 into an arc, the center of the channel approximately corresponding to the circumference of the transfer wheel. While not essential this is found convenient as a ready means of holding the formed blanks snugly within the opening between the teeth of the transfer wheel. A convenient guide is so formed for the blanks while being turned. The holding down plate 14 assists in keeping the blanks in place. As each blank reaches the beginning of the arc 22 it enters an aperture between the teeth of the transfer wheel and the pressure of the nuts behind it forces it forward causing the transfer wheel to rotate. It will be observed that three nuts are engaged by the transfer wheel and within the arc. A preferable arrangement for the specific blanks shown in the drawings is to provide the transfer wheel with twelve teeth and to have the angle formed at its center by radii passing through the first and last nut in the arc 22 equal to sixty degrees. This allows the blanks when passing through the arc 22 to be turned a proper amount. When a blank enters the transfer wheel 13 its face is in contact with the preceding blank and when it leaves the transfer wheel it has been turned or rearranged so that its adjoining face is in contact with the corresponding face of a succeeding nut. The relation of the transfer wheel to the feed wheel is shown in Fig. 7. As shown in Fig. 2 as the nut blank leaves the transfer wheel it drops into a pocket of the succeeding feed wheel 3 by which it is forced through the continuation of the channel 10 and under the succeeding cutter 11 in such a way as to produce a slot at a predetermined angle to the first slot. In like manner the blanks carrying two slots are turned by the second transfer wheel and fed forward by the third feed wheel and under the third cutter in such a way as to produce the third slot in a proper desired relation to the preceding slots.

The transfer wheels need have no external force applied to them and as shown they are not positively driven. Their rotation is caused by the forward movement of the nuts through the channel 10 and the arc 22.

The feed wheels may be rotated by any suitable arrangement of mechanism. Figs. 1 and 2 are broken away so as to show that in the machine illustrated the feed wheels 3

are mounted on transverse shafts 4 carrying worm wheels 23 engaging worms 24 and 31 carried by the shaft 25 driven in any suitable way by the pulley 26. Associated with the pulley 26 is shown a clutch 27 controlling the operation of the shaft and operated by a clutch rod 28 controlled by a clutch lever 29 pivoted at 30 to the bed of the machine. Adjustment may be desirable to allow each feed wheel 3 to be properly arranged to receive nuts in the proper manner from the chute 1 or from a transfer wheel 13. The worm 24 may be turned to set the first feed wheel. The worms 31 associated with the two other feed wheels are loosely mounted on the shaft 25. An extension of each worm 31, as shown in Fig. 5, consists of a disc 32 provided with a plurality of holes 33 any pair of which may be engaged by bolts 34 carried by the disc 35 keyed to the shaft 25. The bolts 34 may be removed and the feed wheels properly set to grasp the formed blanks as they pass from the transfer wheel 13 and force them as so turned through the channel and under the cutter. The bolts 34 may be then set into the proper corresponding holes 33 to hold such adjustment and the worms will turn with the shaft and drive the feed wheels so as to properly force the nuts forward.

The cutters may be rotated in any suitable manner. In the machine of the drawings each cutter 11 is carried on a transverse shaft 36 mounted in a housing 37 provided with a device 38 of a well known type for adjusting the cutters. Mounted on each shaft 36 is a gear 39 at the rear of the machine. An arm 40 carries a shaft 41 carrying a gear 42 and pulley 43. Stud shafts 44 carry adjustable slotted arms 45 in the ends of which are mounted idler gears 46. Each idler gear 46 engages two of the cutter gears 39. By this arrangement as more clearly shown in Fig. 3 when the pulley 43 is driven by any suitable means (not shown) it rotates the gear 42 which engages the first gear 39 which in turn through the gear 46 drives the next gear 39 which in turn through the next gear 46 drives the other gear 39. It will be seen that by this arrangement the cutters are all caused to rotate in the same direction, which in Fig. 1 will be the clockwise direction, so that their lower cutting sides will travel in the direction opposite to the travel of the stream of nuts, which in Fig. 1 is from the left toward the right. The various gears are removably held in place and they may be changed as may the gears 46 and the adjustment of the arms 44 so as to provide for different speeds of rotation or if desirable the individual cutters 11 may be driven at different speeds.

In order to ensure the blanks moving from the chute 1 into the feed wheel 3 it may be

necessary or desirable to provide a directing wheel 5 as illustrated in Fig. 1. This is not essential and it is omitted from Fig. 2. The wheel 5 is provided at its periphery with extending teeth or knobs 6 properly arranged to engage the central apertures in the formed blanks and direct them from the chute 1 into the feed wheel 3. The spacing of the knobs 6 may be such that the formed blanks are kept in contact with each other. The wheel 5 is arranged directly above the outlet of the chute 1 and above the feed wheel 3 so that it ensures a continuous stream of nuts entering the pockets of the feed wheel.

In Figs. 8, 9 and 10 we have shown an optional arrangement in which we provide only one feed wheel 3 which is relied upon to force the nuts entirely through the machine. This arrangement contemplates no feed wheels to receive the nut from the transfer wheels. The single feed wheel used may be driven in any suitable manner. As shown it is arranged on a transverse shaft 47 which carries a gear 48 engaging a gear 49 on the shaft of a pulley 50 which may be driven by any suitable means (not shown) to cause the feed wheel to rotate. Since there is no feed wheel associated with the transfer wheel in this arrangement the overhanging supporting device shown in Fig. 4 for the transfer wheel is not necessary. As shown in Fig. 8 a bolt 51 is tapped into the bed of the machine adjacent the channel 10 and passes through the transfer wheel 13^a and its associated holding down plate 14^a. The transfer wheel 13^a and the holding down plate 14^a are free to rotate on the bolt 51. It may not be necessary but the transfer wheel 13^a as shown in Fig. 8 may now be made considerably thicker than the one shown in Fig. 1, since its thickness is not limited by the necessity for avoiding interference with the underlying feed wheel. The increased thickness of the transfer wheel 13^a allows a larger proportion of the hexagonal nut blanks to engage the transfer wheel more firmly. It is thus more surely possible to transmit the motion from the feed wheel 3 through the nuts engaged by the transfer wheel to the nuts which have already passed the transfer wheel into the continuation of the channel 10.

As shown in Fig. 10 the retaining plates 12 may be flat on both sides and rest on removable side pieces 52^a thicker than those shown in Fig. 6.

In interpreting the appended claims it should be remembered that numerous changes might be made in the apparatus shown without departing from our invention.

We claim as our invention:

1. A bed having a channel comprising a plurality of communicating sections extend-

ing in a substantially straight line, means for forcing nuts through the channel, means for cutting the nuts in each section, and means for rearranging the nuts as they pass from one section to the next.

2. A bed having a channel comprising a plurality of communicating sections extending in a substantially straight line, means for forcing nuts through the channel, means for cutting the nuts in each section, and means for rearranging the nuts as they pass from one section to the next.

3. A bed having a straight channel section, means for slotting nuts in the section, a curved section joining the straight section, a transfer wheel adjacent the curved section for turning the nuts as they pass through the curved section, and means for forcing the nuts through the channel sections.

4. A bed having a straight channel section, means for forcing nuts therethrough, means for slotting the nuts in the section, a curved section to receive the nuts from the straight section, a second straight section to receive the nuts from the curved section, means for slotting the nuts in the second section, a second curved section to receive the nuts from the second straight section, a third straight section to receive the nuts from the second curved section, means for slotting the nuts in the third straight section, and means for guiding the nuts as they pass through each curved section so that they enter the succeeding straight section in a different position from that in the preceding straight sections.

5. A chute carrying nut blanks, a feed wheel below the chute for receiving the blanks, a channel through which the blanks are forced by the feed wheel, and a spacing wheel leading a constant stream of spaced nuts from the chute to the feed wheel.

6. Three cutters in a line with each other, means for feeding nuts to the cutters in succession, and means for rearranging the nuts between the cutters so that the cuts in the nuts are at predetermined angles to each other.

50 7. A bed having a straight channel section, means for forcing nuts therethrough, means for slotting the nuts in the section, a curved section to receive the nuts from the straight section, a second straight section to receive the nuts from the curved section, means for slotting the nuts in the second section, and means for guiding the nuts as they pass through the curved section so that they enter the second straight section in a different position from that in the first straight section.

8. A bed having a straight channel section, means for forcing nuts therethrough, means for slotting the nuts in the section, a curved section joining the straight section,

and a transfer wheel adjacent the curved section for turning the nuts as they pass through the curved section.

9. A bed having a straight channel section, means for forcing nuts therethrough, means for slotting the nuts in the section, a curved section joining the straight section, and a transfer wheel driven by the nuts and adjacent the curved section for turning the nuts as they pass through the curved section.

10. A bed having a channel comprising a plurality of aligned communicating sections, means for forcing nuts through the channel, means for cutting the nuts in each section, means for transferring the nuts from one section to the next, and means for rearranging the nuts as they are transferred.

11. A bed having a channel comprising a plurality of aligned communicating sections, means for forcing nuts through the channel, means for cutting the nuts in each section, means driven by the nuts for rearranging the nuts as they pass from one section to another.

12. A bed having a channel comprising a plurality of aligned communicating sections, means for forcing nuts through the channel, means for cutting the nuts in each section, and means transferring the nuts from one section to the next.

13. A transfer wheel for turning nuts, and a curved guide holding the nuts snugly in the wheel.

14. A transfer wheel for turning nuts, and an overlying plate for holding the nuts in the wheel.

15. A bed having a channel comprising a plurality of aligned communicating sections, means for forcing nuts through the channel, and means for cutting the nuts at a different angle in each section.

16. A bed having a channel comprising three straight sections and two intermediate curved sections, means for forcing nuts through the channel, means in each straight section for cutting the nuts, and means at each curved section for turning the nuts.

17. In a metal working machine of the character described, the combination of a guideway adapted to receive and hold a series of nuts or like articles in alignment as they pass therealong, means for operating on such nuts located in longitudinally spaced relation adjacent said guideway, and means intermediate each pair of said operating means adapted to turn successive nuts through a predetermined angle.

18. In a metal working machine of the character described, the combination of a guideway adapted to receive and hold a series of nuts or like articles in alignment as they pass therealong, means for operating on such nuts located in longitudinally spaced relation adjacent said guideway, and

means intermediate each pair of said operating means adapted to turn successive nuts through a predetermined angle, said last-named means being actuated by the nuts themselves incidentally to their movement along said guideway.

19. In a metal working machine of the character described, the combination of a guideway adapted to receive and hold a series of nuts or like articles in alignment as they pass therealong, means for operating on such nuts located in longitudinally spaced relation adjacent said guideway, and means intermediate each pair of said operating means adapted to turn successive nuts through a predetermined angle, said last-named means including a pivotally mounted member adapted to be engaged by successive nuts and to be actuated thereby incidentally to their movement along said guideway.

20. In a metal working machine of the character described, the combination of a guideway adapted to receive and hold a series of nuts or like articles in alignment as they pass therealong, means for operating on such nuts located in longitudinally spaced relation adjacent said guideway, and means intermediate each pair of said operating means adapted to turn successive nuts through a predetermined angle, said last-named means including a rotatable member adapted to be engaged by successive nuts and to be actuated thereby incidentally to their movement along said guideway.

35 21. In a metal working machine of the character described, the combination of a guideway adapted to receive and hold a series of nuts or like articles in alignment as they pass therealong, means for operating on such nuts located in longitudinally spaced relation adjacent said guideway, means for feeding nuts along said guideway located in advance of each such operating means, and means intermediate each pair of said operating means adapted to turn successive nuts through a predetermined angle and position same for engagement with the corresponding feeding means.

50 22. In a metal working machine of the character described, the combination of a guideway adapted to receive and hold a series of nuts or like articles in alignment as

they pass therealong, means for operating on such nuts located in longitudinally spaced relation adjacent said guideway, means for feeding nuts along said guideway located in advance of each such operating means, and means intermediate each pair of said operating means adapted to turn successive nuts through a predetermined angle and position same for engagement with the corresponding feeding means, said turning means being actuated by the nuts themselves incidentally to their movement along said guideway.

23. In a metal working machine of the character described, the combination of a guideway adapted to receive and hold a series of nuts or like articles in alignment as they pass therealong, means for operating on such nuts located in longitudinally spaced relation adjacent said guideway, means for feeding nuts along said guideway located in advance of each such operating means, and means intermediate each pair of said operating means adapted to turn successive nuts through a predetermined angle and position same for engagement with the corresponding feeding means, said turning means including a pivotally mounted member adapted to be engaged by successive nuts and to be actuated thereby incidentally to their movement along said guideway.

24. In a metal working machine of the character described, the combination of a guideway adapted to receive and hold a series of nuts or like articles in alignment as they pass therealong, means for operating on such nuts located in longitudinally spaced relation adjacent said guideway, means for feeding nuts along said guideway located in advance of each such operating means, and means intermediate each pair of said operating means adapted to turn successive nuts through a predetermined angle and position same for engagement with the corresponding feeding means, said turning means including a rotatable member adapted to be engaged by successive nuts and to be actuated thereby incidentally to their movement along said guideway.
